UNITED STATES PATENT OFFICE.

KARL ENGEL, OF REVERE, MASSACHUSETTS, ASSIGNOR TO UNITED SHOE MACHINERY COMPANY, OF PATERSON, NEW JERSEY, A CORPORATION OF NEW JERSEY.

METHOD OF MAKING SHOES.

1,142,556.

Specification of Letters Patent.

Patented June 8, 1915.

Application filed April 24, 1908. Serial No. 429,013.

To all whom it may concern:

Be it known that I, KARL ENGEL, a subject of the Emperor of Germany, residing at Revere, in the county of Suffolk and Commonwealth of Massachusetts, have invented certain Improvements in Methods of Making Shoes, of which the following description, in connection with the accompanying drawings, is a specification, like reference characters on the drawings indicating like parts in the several figures.

This invention relates to the manufacture of shoes and particularly to the fitting of the shoe stock to the last.

15 Most lasts curve inwardly on the sides at and near the edges at the front end of the heel and it is important in order to produce a well fitted shoe that the upper conform to this inward curvature.

20 In making the uppers of shoes that have outturned sole attaching flanges at the edge of the last, such for example, as the well-known Goodyear welt shoes or "welt shoes" and "stitchdown shoes," certain conditions 25 are met which invite special attention to the fitting of the upper at the front end of the heel portion of the shoe because it is not convenient to fasten the upper in its snugly fitted position at these points at the time it 30 is secured to the innersole at other parts of the shoe. In making the welt type of shoes the upper and the sole attaching flange are fastened to the innersole by a line of stitches called the inseam extending from the front 35 end of the heel on one side of the shoe around the forepart to a similar point on the other side. In stitchdown shoes the innersole frequently terminates, as in the illustrated example, at the front end of the 40 heel and the upper at the heel seat is not secured until the outersole is applied. In making welt shoes the upper is fastened to the innersole at the rear part and sides of the heel by tacks before the inseam is sewed, 45 but the requirements of the inseaming machine render it impracticable to fasten the upper at the front end of the heel until after the inseam has been sewed. The ends of the heel stiffener very frequently spring away 50 from the sides of the last more or less, thus pulling the upper away and increasing the difficulty of obtaining a snug fitting of the upper at the front end of the heel.

An important object of this invention is

to obtain a more perfect fitting of the shoe 55 stock about the sides and over the edge of the last at and near the front end of the heel and the rear ends of the inseam. I have found that by engaging the shoe stock at or near the front end of the heel seat and tightening it against the side and over the edge 60 of the last and holding it while it is secured in tightened position, a material improvement in the fit and in the appearance of the shoe can be obtained. In its broadest aspects 65 the invention contemplates tightening and securing the upper at one side of the shoe at a time, but I prefer to perform this operation at the two sides of the shoe simultaneously. While the shoe stock may be 70 engaged and manipulated in any suitable way to secure the firm fitting of the stock and to hold it in desired position while it is secured, I have found it advantageous to engage the upper and flange in the crease between 75 their adjacent faces. By so doing the engaging device may by suitable movements be made to press or clamp the upper and stiffener against the side and edge of the last and to force the stock inwardly over the 80 edge and hold it in position to be secured. The securing of the parts in tightened position may be effected in any desired way. I prefer in the manufacture of stitchdown 85 shoes to practise this invention in connection with the operation of laying the outersole and to coat with cement one or both of the adjacent faces of the outersole and the flange. Then when the upper has been tightened to the last and while it is so held 90 the outersole is applied and caused by the cement to adhere to the flange and bind the parts in position. Subsequently the outersole is stitched to the flange to fasten it permanently, the stitching being preferably located in or near the angle formed by the flange and upper whereby the upper is 95 surely held in place in the finished shoe.

In making welt shoes this invention may be practised in connection with the sole laying operation, as described with relation to the manufacture of stitchdown shoes or it may constitute an earlier operation and the upper may be fastened to the innersole, by tacks or other fastenings while it is held 100 tightened over the edge of the last.

A further object of this invention is to obtain a better fitting and securing of the

outersole in shoes that have the outersole fastened to an outturned flange or welt connected to the upper. It is the practice in the sole laying operation to position the outer-
 5 sole upon the shoe bottom and, by means of a rubber or other pad or form, to press the outersole firmly against the shoe bottom and hold it under pressure to cause it to become molded approximately to the shape of the
 10 shoe bottom and to allow time for the cement, with which one or both of the adjacent faces of the outersole and shoe have been previously coated, to set sufficiently to hold the outersole temporarily in proper relation to
 15 the shoe. The shoe is afterward presented to a sewing machine by which the outersole is sewed through and through to the flange. The last is within the shoe during the sole laying operation and presents a firm sup-
 20 port for the shoe bottom inside the marginal flange. The last, however, furnishes no support for the flange which therefore yields to the pressure of the pad, permitting the sole edge to bend upwardly all the way around
 25 the shoe. The flange has an initial tendency to curl up at the convex end portions of the shoe and usually in welt shoes it is specially treated at the toe by beating it or slashing it to cause it to stand outright in proper
 30 position to be sewed to the outersole. The pressure of the marginal portion of the sole against the unsupported flange, of course, tends to curl the flange up again.

It is a very important characteristic of
 35 the preferred practice of this invention that the shoe stock is so engaged that the sole attaching flange is supported during the sole laying operation against the pressure of the sole and the pad of the machine. The flange
 40 at the rear end of the shoe can advantageously be supported by the engaging device that tightens the upper over the last at the front end of the heel and which for this purpose is arranged to embrace the heel portion
 45 of the shoe and approximately fit the flange crease. The flange at the toe or forepart of the shoe can be supported by a similarly formed device. By supporting the flange the sole is prevented from being pressed out
 50 of place at its marginal portion and the flange is retained in its proper outstanding position, if it has already assumed that relation to the shoe, or if it is more or less curled up it can be bent back to its right
 55 position by the supporting means. If the adjacent surfaces of the flange and outersole are coated with cement they of course stick together during the sole laying operation. This is of great importance as it provides
 60 that the flange shall be in the right relation to the margin of the outersole when the shoe is presented to the sole sewing machine.

The invention will be more fully explained in the following description, reference being
 65 had to the accompanying drawings in which

is shown one form of apparatus by the aid of which the invention may be practised.

The apparatus is not herein claimed as it forms the subject-matter of another application, Serial No. 428,123.

Figure 1 is a perspective view of an apparatus that may be employed in practising this invention. Fig. 2 is a plan view, partly in section. Fig. 3 is a side elevation showing the flange supporting devices and the sole supporting devices in position with relation to the shoe and sole respectively. Fig. 4 is a vertical section on line 4—4 of Fig. 3 showing the jaws supporting the flange and holding the shoe stock inwardly with relation to the last at the front end of the heel seat of a stitchdown shoe, the sole being supported below the shoe. Fig. 5 is a similar view showing the jaws supporting the flange against the pressure of the sole during the sole attaching operation. Fig. 6 is a view similar to Fig. 4 but showing a welt shoe being operated upon. Fig. 7 shows the curled up condition of the welt at the toe of a welt shoe after the welt has been stitched on and before the sole is attached. Fig. 8 is a view showing the action in straightening the welt at the toe end of a welt shoe and compressing it against the sole in the sole laying operation.

In the illustrated machine which may be used in practising the invention a shoe having a last within it is supported between the clamps 2 and 4 and against the abutment 5 which engages the last. These parts are carried adjustably by the head 6 which is movable relatively to the sole support 8, which has a yielding and flexible pad 10 preferably of rubber for pressing the sole upon the shoe.

The clamp 2 comprises the jaws 12 which are shaped to embrace the heel portion of the shoe. The edges of the jaws next to the shoe are tapered to enter the crease between the upper on the side of the shoe and the upper face of the sole attaching flange, and may be formed as shown to fit the crease approximately, presenting an inseam engaging inner edge and a flange supporting lower surface, and being of suitable length to act upon the sides of the heel portion of the shoe at and adjacent to the front ends of the heel stiffener. The jaws are pivotally supported at 14 at the rear of the shoe and are connected to devices that may be operated manually or automatically for swinging them toward the shoe and causing them to press the shoe stock at and adjacent to the heel stiffener ends, preferably including that between the heel seat tacks and the inseam, inwardly with relation to the shoe stock located in the shank. Preferably the jaws are normally pressed yieldingly by a spring 15 in the direction to grip the shoe when it is inserted between them and the abutment 5 and to clamp the upper and stiffener to the

side of the last to tighten the upper against or over the edge of the last by their engagement with the bottom of the crease. The jaws swing under the yoke 16 which is 5 connected to the head 6 and forms a rigid overhanging abutment for the free end portions of the jaws.

The clamp 4 comprises the jaws 20 which are relatively movable to adapt themselves 10 to the width and shape of the forepart of the shoe, being guided in the plate 22 and held toward each other by springs 24. The jaws 20 are shaped at their inner edges similarly to the jaws 12 to fit into the flange crease 15 and present lower surfaces to rest upon the upper face of the flange or welt, furnishing it a firm support against the pressure of the sole in the sole laying operation. The jaws 20 with the plate 22 are arranged for movement under the abutment 25 by the lever 26 to force the jaws into the crease, seat them in position to straighten a curled up flange 20 or welt and to hold it straight and upright during the sole attaching operation.

In practising the invention with the aid 25 of the described apparatus the shoe is inserted from below rearwardly into the clamp 2. The jaws may be opened for the purpose of receiving the shoe and when they are 30 closed their shaped edges will enter the flange crease and exert pressure inwardly against the shoe stock to clamp the upper and heel stiffener to the sides of the last and force the stock against or over the edge of 35 the last, tightening the upper and holding it in position to be secured, as shown for example in Figs. 4 and 6. The jaws 12 will preferably be so constructed and arranged 40 that they will press the upper at and adjacent to the front end of the heel seat inwardly with relation to the shoe stock in the shank, as indicated in Fig. 3. They can thus force into fastened position the shoe stock 45 at and near the front ends of the heel stiffener and hold it during the compression to which the stock of the shoe bottom is subjected during the sole laying operation. In 50 welt shoes the jaws engage at the edge of the shoe the stock between the heel seat tacks and the ends of the inseam and hold it while it is being secured. This fastening of the upper is effected as herein shown, see 55 Fig. 5, by attaching it to the sole while it is held. Cement is applied to one or both of the adjacent faces of the flange and sole and these surfaces pressed together and held until the cement sets enough to hold the upper and heel stiffener from slipping or 60 springing outwardly from the position to which they have been pressed. The sole forms a binder extending across the shoe and connecting the flange at the two sides. The shoe stock might be secured in other 65 ways, as for example, by tacks or stitches and might be fastened at one side of the

shoe at a time. After the shoe has been thrust into the clamp 2 the toe end is raised between the jaws of the clamp 4 and these jaws are caused by their springs 24 and the lever 26 to enter the flange crease, between the upper and the upper face of the flange or welt, insuring the correct relation of the latter to the upper and tightening the upper snugly to the edge of the last by their inward pressure. When the head 6 and the 70 sole support 8 are relatively actuated to force the shoe and sole together the jaws 12 and 20 firmly support the welt against the pressure of the sole and the pad 10, preventing the sole from being bent up at the edges 75 and preventing the welt from curling or yielding upwardly. The sole and the welt are firmly clamped and are compressed between the jaws and the pad and this pressure on the welt reduces its tendency to curl up 80 when the shoe is released. Preferably, however, as before stated, the adjacent faces of the flange and sole are coated with cement and the pressure is maintained long enough to cause them to adhere securely. By bending 85 or straightening out the curled up welt all about the toe portion of the shoe at the same time the outer edge of the welt is stretched and the force applied during the sole laying operation compresses and tends 90 to confirm more or less the stretched condition of the welt. The permanence of this 95 stretched condition is made certain by attaching the welt to the sole, as by means of the cement preferably employed.

It will be understood that my novel 100 method is not limited to practice by means of the apparatus shown and described herein as that apparatus is illustrated and its use explained merely for the purpose of 105 showing one way in which the method may be practised.

The invention is of course not limited to 110 any apparatus and the performance of the succession of steps in which my improved method consists is within my invention in whatsoever manner and by whatsoever means these steps may be performed.

Having explained the nature of this invention and fully described how it may be 115 practised, I claim as new and desire to secure by Letters Patent of the United States:—

1. That improvement in the art of making a shoe having a flange projecting outwardly from the upper at the edge of the shoe bottom, which comprises connecting a sole to the upper by fastening means extending along the forepart and shank and terminating at points remote from the rear end of the shoe and mounting the shoe on a last, 120 engaging the shoe stock in the crease between the side of the upper and the flange at and near the rear of said fastening means and forcing the stock inwardly to tighten it over the last at the front end of the heel seat 125 130

- relatively to portions located forwardly thereof, and then securing the upper to maintain it in said tightened condition.
2. That improvement in the art of making a shoe having a flange projecting outwardly from the upper at the edge of the shoe bottom and a crease between said flange and the side of the upper, which comprises connecting a sole to the upper by fastening means extending along the forepart and shank and terminating at points remote from the rear end of the shoe, engaging the shoe stock in said crease at or adjacent to the end of the heel stiffener and pressing the upper inwardly at the point of engagement relatively to the portion of the upper in advance of said point to conform the front ends of the heel stiffener to the last, and then securing the stock to maintain it in said conformed relation.
3. That improvement in the art of making shoes which comprises assembling upon a last shoe materials comprising an upper and an innersole and connecting the upper to the innersole by a seam extending from a point at or near the front end of the heel seat on one side around the forepart to a similar point on the other side, then engaging the upper at or adjacent to an end of said seam and by lateral pressure directed inwardly tightening the upper at the point of engagement relatively to portions of the upper located forwardly of said point to conform the materials to the last, and then securing the upper adjacent to said point of engagement while the materials are held in said tightened condition.
4. That improvement in the art of making shoes which comprises assembling upon a last shoe materials comprising an upper and an innersole and connecting the upper to the innersole by a seam extending from a point at or near the front end of the heel seat on one side around the forepart to a similar point on the other side, then engaging the shoe materials at or adjacent to the ends of said seam on both sides of the shoe simultaneously and pressing the upper inwardly at the points of engagement relatively to portions of the upper located forwardly of said points, and then securing the upper adjacent to said points of engagement before the pressure is released.
5. That improvement in the art of making a shoe having a flange projecting outwardly from the edge of the upper and a crease between the upper and the flange, which comprises securing the upper at the forepart and shank to an innersole, while leaving a rear portion of the upper relatively loose, and mounting the shoe on a last, engaging the shoe stock in said crease at opposite sides of the shoe rearwardly from points at or near the ends of the heel stiffener and pressing the stock inwardly to tighten the loose upper against the sides of the last, and securing the upper adjacent to said points of engagement while said pressure is maintained to conform the front ends of the heel stiffener snugly to the last.
6. That improvement in the art of making welt shoes which comprises connecting the upper at the forepart and shank to an innersole while leaving a rear portion of the upper relatively loose, engaging the shoe in the welt crease at or adjacent to said loose portion of the upper at opposite sides of the shoe and pressing the stock inwardly over the last to tighten it, and then securing the upper before the pressure is released to maintain the rear portion of the upper and the welt tightened over the last bottom.
7. That improvement in the art of making welt shoes which comprises connecting an innersole to the upper by a line of fastenings extending along the forepart and shank and terminating at points remote from the rear end of the shoe, engaging the shoe stock adjacent to the opposite ends of the line of fastenings and moving it relatively to portions of the upper located in advance of said points in a direction inwardly over the last bottom to tighten it at opposite sides of the shoe simultaneously, and then securing the upper in said position to maintain it tight about the last at the front end of the heel seat.
8. That improvement in the art of making a shoe having a sole attaching flange projecting outwardly from the upper at the shoe bottom, which comprises connecting the upper to an innersole along the shank and forepart by a line of fastenings terminating near the heel breast and applying cement to the connected materials on the marginal portion of the shoe bottom, pressing the stock against the sides and over the edges of the last bottom through engagement with the opposite sides of the shoe in the flange crease and then, while said pressure is maintained, pressing the cement coated surfaces including the flange at opposite sides of the shank into engagement with a connecting member to hold the upper in lasted position.
9. That improvement in the art of making a shoe having an outturned sole attaching flange which comprises embracing the shoe about the heel portion of the last and in the crease between the upper and said flange at and adjacent to the ends of the heel stiffener, relatively moving the last and the embraced heel portion of the upper lengthwise and transversely of the shoe to tighten the upper about the last while leaving portions of the upper in the shank free from said tightening pressure and, while said pressure is maintained, securing an outersole to the flange to hold the upper in lasted position.
10. That improvement in the art of mak-

- ing a shoe having an outturned sole attaching flange which comprises connecting an innersole to the upper by a line of fastenings extending along the forepart and shank and terminating at points remote from the rear end of the shoe, engaging the stock in the flange crease at or near the rear of said fastenings and pressing the upper inwardly while supporting the flange upon its upper side, temporarily attaching an outersole to the flange while the flange is thus supported and then releasing the flange and outersole from said engagement and pressure and sewing the outersole to said flange.
11. That improvement in the art of making a shoe having an outturned sole attaching flange which comprises connecting the upper along the forepart and shank to an innersole, applying a previously formed outersole to the shoe bottom with a coating of cement between adjacent portions of said outersole and flange, clamping the flange at the toe end tightly down upon the outersole by pressure applied to continuous portions 25 of its upper face substantially throughout the width of such face to straighten out any curled up portions of the flange, holding the flange and outersole under pressure a sufficient time to permit the cement to set and 30 maintain the flange in the straightened condition, and permanently sewing the outersole to the straightened flange.
12. That improvement in the art of making a shoe having an outturned sole attaching flange, which comprises bending the curled up toe portion of the flange outwardly and downwardly and supporting it upon its upper side, relatively moving the shoe and a previously formed sole to bring the sole into position for attachment to said flange, pressing the sole and the flange together to flatten and stretch the outer edge portion of the flange and, while maintaining the flattened stretched condition of the flange, temporarily securing the flange and the sole together under pressure and then releasing the pressure and permanently sewing the sole to the flange.
13. That improvement in the art of making a shoe having an outturned sole attaching flange which comprises subjecting the toe portion of the materials to lateral inward pressure applied in the crease between the upper and the flange while simultaneously supporting the flange upon its upper side and, while maintaining said pressure and support, relatively moving the flange
- and a previously formed sole to press the sole into position for attachment to the flange and temporarily securing the sole and the flange together under pressure, and then releasing the flange and sole from pressure and permanently sewing them together.
14. That improvement in the art of making a shoe having an outturned sole attaching flange upon the upper which comprises engaging and forcing the flange inwardly over the edge of the last bottom to tighten the upper over the last, bringing a sole into position for attachment to the flange while the upper is held in said tightened condition, subjecting the flange and the marginal portion of the sole to pressure in a direction substantially perpendicular to the plane of the sole and performing a temporary sole attaching operation and then releasing the pressure and permanently sewing the sole to the flange.
15. That improvement in the art of making a welt shoe which comprises straightening out the curled up portions of the welt about the different portions of the toe end of the shoe at substantially the same time to stretch the outer edge of the welt and supporting said portions of the welt around the toe substantially throughout its width upon its upper side, pressing the welt while thus supported into engagement with a relatively inflexible member and attaching it to said member to hold it from recurling when the pressure is released, and then releasing the pressure and permanently sewing the sole to the straightened welt.
16. That improvement in the art of making a shoe having an outwardly projecting sole and upper connecting flange thereon, which comprises engaging the shoe stock in the crease between the upper and said flange and forcing the shoe stock inwardly at opposite sides of the shoe simultaneously to tighten it at the front end of the heel seat relatively to the upper in the shank, temporarily securing the upper while it is held under tension, releasing the tension on the shoe stock, and then permanently sewing the flange to a sole.

In testimony whereof I have signed my name to this specification in the presence of two subscribing witnesses.

KARL ENGEL.

Witnesses:

H. DORSEY SPENCER,
FREDERICK L. EDMONDS.

It is hereby certified that in Letters Patent No. 1,142,556, granted June 3, 1915, upon the application of Karl Engel, of Revere, Massachusetts, for an improvement in "Methods of Making Shoes," errors appear in the printed specification requiring correction as follows: Page 1, line 87, for the word "coact" read *coat*; same page, lines 97-98, for the word "sesurely" read *securely*; and that the said Letters Patent should be read with these corrections therein that the same may conform to the record of the case in the Patent Office.

Signed and sealed this 8th day of February, A. D., 1916.

[SEAL.]

R. F. WHITEHEAD,

Acting Commissioner of Patents.
